Attest

AARON VAN GUYSLING, OF WEST ALBANY, NEW YORK.

Letters Patent No. 84,023, dated November 10, 1868.

IMPROVED RAILWAY-CHAIR AND SUPPORT.

The Schedule referred to in these Letters Patent and making part of the same.

To all whom it may concern:

Be it known that I, AARON VAN GUYSLING, of West Albany, in the county of Albany, and State of New York, have invented a new and useful Improvement in Railroad-Chairs and Supports; and I do hereby declare that the following is a full, clear, and exact description thereof, which will enable others skilled in the art to make and use the same, reference being had to the accompanying drawings, forming a part of this specification.

Figure 1 is a top view of a portion of a railroad-track to which my improvements have been attached.

Figure 2 is a vertical cross-section of the same, taken through the line $z z$, fig. 1.

Figure 3 is a vertical cross-section of the same, taken through the line $y y$, fig. 1.

Figure 4 is a detail sectional view of the same, taken through the line $z z$, fig. 1.

Similar letters of reference indicate corresponding parts.

My invention has for its object to improve the construction of railroad-chairs and their supports, so as to furnish a substantial, reliable, and elastic support for the rails, which will hold said rails securely in place, and, at the same time, prevent the jar, now so universally experienced in railroad-riding; and it consists in the construction of the various parts of the chairs and their supports as hereinafter more fully described.

A are the supports, which are made in the form of hollow iron columns, closed at the upper or at both ends, and which are securely set in the ground in a vertical position.

If desired, the hollow supports A may be made short, with their lower ends attached to or formed solid with a hollow metallic bar or tie, B , which rests upon or is embedded in the ground, as shown in fig. 3.

C are the chairs, which are made in the form of metallic caps, fitting and resting upon the upper ends of the supports A .

c^1 are lips, formed solidly upon the upper side of the chairs C , and which overlap the edge of the base-flange upon one side of the rails.

c^2 is a detachable lip, secured to the upper side of the chairs C by key-bolts D , as shown in the drawings, or by other convenient and substantial means.

The opposite chairs are connected to each other by an iron bar or tie, E , as a guard against the possibility of the rails spreading.

In the opposite sides of the chairs C , just below the

solid top of said chairs, are formed slots, through which are passed wooden blocks, F , which are thus interposed between the solid tops of the chairs C , and the solid tops of the supports A , to form an elastic support for the weight of the passing train.

G are rubber blocks, which may be placed between the wooden blocks F and the tops of the supports to give further elasticity to the chairs.

By this construction, by removing the wooden blocks F , the rubber block G may be removed and replaced through the hole or holes in the side or sides of the chairs C , without removing the chairs C from the supports A , or disturbing the rails.

If desired, the rubber blocks G may be used with the wooden blocks F , but in this case the hole or holes through the side or sides of the chairs C , through which the said rubber blocks are inserted and removed, should be closed with a slide, H , or other convenient device as shown in fig. 4.

It should be observed that the supports A may, if desired, be replaced with wooden or stone supports, I prefer the construction of said supports first described as being more substantial and satisfactory in use.

Having thus described my invention,

What I claim as new, and desire to secure by Letters Patent, is—

1. The railroad-chair support, consisting of the hollow supports A , connected by the tube B , the chairs C having the fixed lip c^1 and the detachable lip c^2 , the key-bolt D , the rubber block G , the wooden block F and the connecting-bar E , said chairs being slotted to receive the bent ends of the connecting-bar, and for the passage of the wooden blocks, all arranged as described for the purpose specified.

2. The chair C , fitting over the hollow support A and constructed as described, having the fixed lip c^1 and the detachable lip c^2 , and the key-bolt D , and provided with an opening in its side for the introduction of the rubber block G , which is kept in place by the sliding door as herein set forth, for the purpose specified.

3. The combination of the horizontal metallic tie, B , with the vertical hollow supports A , substantially as herein shown and described, and for the purpose set forth.

AARON VAN GUYSLING
